UNITED STATES PATENT OFFICE.

FRANZ HANSHAMMER, OF CONCORD, NEW HAMPSHIRE, ASSIGNOR TO
FREDERICK BECK, OF NEW YORK, N. Y.

DESIGN FOR DECORATIVE FRIEZE.

SPECIFICATION forming part of Design No. 32,938, dated July 10, 1900.

Application filed April 14, 1900. Serial No. 12,945. Term of patent 3½ years.

To all whom it may concern:

Be it known that I, FRANZ HANSHAMMER, a subject of the Emperor of Germany, residing in the city of Concord, in the State of New Hampshire, have invented and produced a new and original Design for a Decorative Frieze, of which the following is a specification, reference being made to the accompanying drawing, forming part thereof.

1. The drawing represents a front plan view of the design.

The leading features of the design consist of a number of female figures grouped together and representing the idea of mirth (1 2 3 4 5 6 7 8) and also a number of figures of children grouped together and representing the idea of youth, (9 10 11 12,) the whole showing the warmth and glow of summer life

and happiness. These decorative figures are placed on a groundwork or base rectangular 20 in outline.

The whole design represents summer in the forms of mirth and youth.

Having described my invention, what I claim as new, and desire to secure by Letters 25 Patent, is—

The design for a decorative frieze, as herein shown and described.

Signed at New York city, in the county of New York and State of New York, this 23d 30 day of March, A. D. 1900.

FRANZ HANSHAMMER.
